J. H. ACKROYD,
GAS BURNER AND BODY COVERING THEREFOR,
APPLICATION FILED MAY 1, 1919.

1,335,869.

Patented Apr. 6, 1920.

INVENTOR
JOHN H. ACKROYD
BY *George E. Wall*
ATTORNEY

UNITED STATES PATENT OFFICE.

JOHN H. ACKROYD, OF MILFORD, CONNECTICUT.

GAS-BURNER AND BODY-COVERING THEREFOR.

1,335,869.

Specification of Letters Patent.

Patented Apr. 6, 1920.

Application filed May 1, 1919. Serial No. 293,938.

To all whom it may concern:

Be it known that I, JOHN H. ACKROYD, a citizen of the United States, residing at Milford, in the county of New Haven and 5 State of Connecticut, have invented certain new and useful Improvements in Gas-Burners and Body-Coverings Therefor, of which the following is a specification, reference being had therein to the accompanying 10 drawings.

The present invention relates to gas burners of a type such as employed with cooking stoves, cooking tops, hot plates or the like on which cooking utensils are heated.

15 The chief objects of the invention, among other things, are to produce a simple, efficient and economical burner; to adapt the burner for general cooking use; and to provide means to facilitate cleaning of the 20 burner.

The improved burner as a complete article, comprises a hollow head, providing a gas distributing chamber having outlets through ports provided in a multiplicity of 25 burner elements, such as bosses or tubes projecting upwardly from the top of the burner head and being spaced and grouped thereon in a particular manner so as to define air passages therebetween. A tubular shank 30 extends outwardly from said head in horizontal alinement therewith and said shank terminates in a cylindrical enlargement, the interior of which forms an air intake chamber, communicating through the passage 35 provided by the bore of said shank, with the gas distributing chamber in the burner head. The head and shank constitute the body of the burner and for the body a separable covering plate is provided, which 40 plate, when in position for service, covers the upper surface of the body, the top surface of the head being covered around the bases of the bosses or tubes.

The novel features of the improved burner 45 generally described above will be hereinafter more particularly described in detail and defined by the appended claims.

In order that the invention may be more clearly understood reference is made herein 50 to the accompanying drawings, illustrating embodiments of the invention and in these drawings;

Figure 1 is a top plan view of the complete burner;

55 Fig. 2 is a longitudinal section, taken upon line 2-2 of Fig. 1;

Fig. 3 is a detail plan view of a modification of a flat plate for covering the head of the burner alone; and

Fig. 4 is a plan view showing another 60 modification, consisting of a covering plate shaped to fit and cover the top of the burner shank.

In the embodiments of the invention illustrated, 1 represents the head of the burner, 65 tubes or bosses 2, each having a longitudinal central bore 3 providing outlet ports for gas passing through the distributing chamber 4 within said head. A tubular shank 5 extending outwardly from said head and 70 formed integral therewith terminates in an enlarged end 6 providing the air intake chamber 7, which communicates by means of the bore 8 of the shank with the distributing chamber 4. Gas may be supplied to the 75 burner through the usual gas supply nozzle 9 and the usual adjustable cap 10 is employed for covering the end of the enlargement 6, both of these parts having the usual registering openings whereby the supply of 80 air admitted for mixture with the gas may be regulated.

The burner body, inclusive of the burner tubes or bosses, is preferably cast in one piece. The lugs 11 and 12 formed on the 85 bottom of the head 1 provide alternative means for securing the burner in place, the lug 11 being adapted for engagement in the hole of a supporting member, not shown, or the lugs 12 may be adopted and when used 90 they rest on a cross bar 13, for example.

The burner tubes 2 are arranged in a group on the top of the head 1, the tops of all the tubes being substantially on the same level. The tubes are spaced an equal distance apart, to form a hexagonal or other shaped figure, whereby the tubes may be so located or grouped so that straight passages, such as indicated by broken lines *a* and *b* are defined, and these passages serve to admit an equal amount of air to all the flame jets, consequently the jet 14 at the center of the group will burn with the same uniformity and intensity as the outside jets 15, thus distributing heat equally to the cooking 105 utensil 16, for example, and shown in broken lines (Fig. 2) as being supported on a grid or open top 17 over the burner.

It should be understood the height of the burner tubes above the top surface of 110 the head 1 is determined by the capacity of the burner and the height of the tubes

establishes the area of the air passages *a* and *b*. In the illustrative embodiment of the invention the capacity of the burner is represented by the number of jets, thirty-seven in all, and the height of the tubes, as shown, is substantially correct for a burner of that size and capacity. If another row of tubes is added all around the burner, the capacity thereof will be represented by sixty-one. A burner of such capacity will consume proportionately more air, consequently the height of the burner tubes should be accordingly greater to establish air passages of greater area.

In a burner having, for example, one less row of jets than the illustration herein, the relative height of the burner tubes would be in accordance with the required area of the air passages. When the burner is in use the air passages *a* and *b* frequently become obstructed by grease and carbon resulting from overflow in cooking, or from other causes, thus lessening the efficiency of the burner. Periodical cleaning would obviate this defect but for the reason that the burner must be dismounted and bodily removed for cleaning, which is an inconvenience, proper care is not given to the burner. According to the present invention means are provided to facilitate cleaning of the burner and such means consists of a covering plate having a flat head piece 19 and a tail piece 20. The head piece 19 is provided with perforations 21 grouped and otherwise conforming with the burner tubes 2 so that this piece will fit over the said tubes and completely cover the top surface 18 of the head piece 1. The tail piece 20 rests on the flat ledge 22 of the burner shank 5 and covers the top of this latter member. A depending flange 23 on the underside of the covering plate serves the purpose of preventing creeping of the grease so that it cannot collect on the underside of the plate, but is caused to drop from the depending flange clear of the burner body. The covering plate is self-retained in place by means of the engagement of the burner tubes or bosses 2 in the perforations 21 and being so held said plate is readily removed for the purpose of cleaning. The said covering plate may be made in sections and accordingly Figs. 3 and 4 show respectively the head piece 19 and the tail piece 20 as being composed of separate members. The flange

23 extends completely around the plate 19, and when applied to the burner the flange lies below the shoulder 24 and the end edge 25 of the tail piece 20 lies below said flange to provide an overlapping joint. The tail piece 20 or shank covering is shaped to fit the shank and in this case the ledge 22 may be dispensed with if desired. The covering plate becomes heated to a sufficient temperature to quickly burn to an ash any grease or other matter which may fall upon it. This ash may readily be blown or brushed off while the plate is in its position on the burner body, or the plate may be removed for cleaning.

I do not intend to be restricted to the exact embodiment of the invention shown, but desire to cover all constructions coming within the scope of the annexed claims.

Having described my invention, what I claim as new and desire to secure by Letters Patent, is:

1. In a gas burner; a body; a plurality of burner elements spaced apart and projecting above said body so as to define air passages therebetween; and a covering plate for said body having perforations therein and arranged in relation to said body so that said burner elements project through said perforations.

2. In a gas burner, a body; a plurality of burner elements spaced apart and projecting above said body so as to define air passages therebetween; and a plate for covering said body located adjacent to the bases of said burner elements at the bottom of said air passages.

3. In a gas burner, a body; a plurality of burner elements spaced apart and located on said body so as to define air passages therebetween; a movable plate for covering said body around the bases of said burner elements; and a depending flange on said plate.

4. In a gas burner; a body; a plurality of burner elements spaced apart and projecting above said body so as to define air passages therebetween; and a flanged cover plate for said body having perforations therein and arranged in relation to said body so that said burner elements project through said perforations.

In testimony whereof I have hereunto affixed my signature.

JOHN H. ACKROYD.
